Primary Examiner — Manpreet Matharu*Assistant Examiner* — Mojtaba Tehrani(74) *Attorney, Agent, or Firm* — LeClairRyan(57) **CLAIM**

The ornamental design for vehicle wheel, as shown and described.

DESCRIPTION

FIG. 1 is a top perspective view of a vehicle wheel showing our new design; and,

FIG. 2 is a front elevational view thereof.

The broken lines and the area enclosed by them in the figure drawings represent unclaimed environment only and form no part of the claimed design.
